UNITED STATES PATENT OFFICE

130,428

DESIGN FOR A CLOCK

Ray A. Schober, Chicago, Ill., assignor to Premium Products Mfg. Co., Chicago, Ill., a partnership consisting of Ray A. Schober and Nate Asher

Application May 1, 1941, Serial No. 100,727

Term of patent 3½ years

To all whom it may concern:

Be it known that I, Ray A. Schober, a citizen of the United States and resident of Chicago, in the county of Cook and State of Illinois, have invented a new, original, and ornamental Design for a Clock, of which the following is a specification, reference being had to the accompanying drawing, forming a part thereof.

Fig. 1 is a front perspective view of a clock showing my new design.

Fig. 2 is the top view of the same.

The posterior view is plain.

I claim:

The ornamental design for a clock, substantially as shown and described.

RAY A. SCHOBER.
